UNITED STATES PATENT OFFICE.

HJALMAR G. CARLSON, OF WORCESTER, MASSACHUSETTS, ASSIGNOR TO ROCKWOOD SPRINKLER COMPANY OF MASSACHUSETTS, OF WORCESTER, MASSACHUSETTS, A CORPORATION OF MASSACHUSETTS.

AIR EXHAUSTER FOR DRY-PIPE SYSTEMS.

Application filed August 10, 1920, Serial No. 402,579. Renewed June 30, 1924.

To all whom it may concern:

Be it known that I, HJALMAR G. CARLSON, a citizen of the United States, residing at Worcester, in the county of Worcester and 5 State of Massachusetts, have invented a new and useful Air Exhauster for Dry-Pipe Systems, of which the following is a specification.

This invention relates to an air exhauster 10 for sprinkler equipment operated on the dry pipe system. In such dry pipe systems, the distribution pipes are normally filled with a comparatively large quantity of air under sufficient pressure to exclude water from the 15 system, so long as all sprinklers remain closed. When a sprinkler opens, air commonly escapes through the open sprinklers, and water flows in to fill the opened pipe and operate the sprinkler.

20 It is of course desirable that the water should replace the air in the pipe in the shortest interval of time after the sprinkler opens and also that the air should escape in such a manner that it will not quicken the 25 fire or scatter sparks therefrom.

It is the general object of my invention to provide an exhaust device for dry pipe systems, by which this desirable end may be effectively attained. With this general object in view, an important feature of my 30 invention relates to the provision of an exhaust chamber directly connected to the dry pipe system, an exhaust valve for said chamber, and pressure controlled devices for 35 opening said valve. A further feature of my invention relates to the provision of a second or air storage chamber preferably adjacent said exhaust chamber, the valve opening devices being controlled by relative difference in pressure between said chambers.

40 My invention further relates to certain arrangements and combinations of parts which will be hereinafter described, and more particularly pointed out in the appended claims.

45 A preferred form of my invention is shown in the drawing which is a sectional elevation of my novel air exhauster, certain parts of the pipe system being also indicated.

50 Referring to the drawings, I have shown my invention applied to a sprinkler system comprising the usual main distributing pipe or riser 10 from which branch distributing pipes 11 convey water to the sprinkler heads,

one of which is shown at 12. I have also 55 shown a return pipe 13 preferably connected at the highest point of the riser 10, said pipe being provided with a drip valve 14.

My improved air exhauster comprises a casing 15 having an air exhaust chamber 16 60 and an air storage chamber 17 formed therein. An unobstructed inlet pipe 18 connects the pipe 13 to the exhaust chamber 16, the exhaust chamber being also provided with an exhaust pipe 19 normally closed by 65 an exhaust valve 20 mounted on a valve frame 21 pivoted at 22 to the casing 15.

The chambers 16 and 17 are separated by a diaphragm 23 on which is mounted a valve lifter 24. The upper end of the lifter 24 is 70 positioned to engage a cap 25 threaded in an extension of the valve frame 21 and held in adjustment by a set screw 26. The valve lifter 24 is provided with a restricted passage or bleed opening 27, communicating at 75 its lower end with the chamber 17 and at its upper end with the chamber 16. A drip valve 28 of the usual type is also provided for the storage chamber 17.

Having described the details of construction of my improved air exhauster, I will now describe the operation thereof. Under normal conditions, the valve 20 is firmly seated to close the exhaust pipe 19, and the cap 25 is slightly removed from the end of 85 the lifter 24. The exhaust chamber 16 is also normally filled with water up to the level of the inlet connection 18. The air in the exhaust chamber 16 is of the same pressure as the air in the dry pipe system, commonly from forty to fifty lbs. per square 90 inch, and the air in the chamber 17 is also at the same pressure, due to the free connection through the bleed opening 27 between the two chambers.

Assuming that a sprinkler 12 is opened, air will escape through the sprinkler head more rapidly than air can flow from the storage chamber 17 through the bleed opening 27 to the exhaust chamber 16. The pressure in the chamber 16 will therefore fall below that of the chamber 17, with resulting upward movement of the diaphragm 23. Such movement will force the valve lifter 24 against the cap 25 with two important 100 results.

In the first place, the cap 25 immediately closes the bleed opening 27 and prevents any

further reduction in pressure in the storage chamber 17. In the second place, the cap 25 is moved upward, carrying with it the valve frame 21 and the exhaust valve 20, thus 5 opening the exhaust pipe 19, through which air will escape from the dry pipe system with great celerity.

As the air escapes through the pipe 19, water enters the system through the riser 10. 10 When this is filled, a portion of the water flows into the return pipe 13 and through the inlet pipe 18 to the exhaust chamber 16. The water rushing into the chamber 16 quickly closes the valve 20, both by its own 15 momentum and also by overcoming the pressure in the storage chamber 17, returning the valve lifter 24 to its lower position. The parts remain in this position until the water is shut off and the sprinkler heads 20 are closed.

The valve 14 may then be opened, draining the water in the pipe 18 and also draining the exhaust chamber 16 down to the level of the inlet pipe 18. The water remaining in the chamber 16 is of advantage 25 in sealing the valve 14. Any slight leakage through the bleed opening 27 may be removed from the chamber 17 by opening the valve 28. The valves 14 and 28 are then 30 closed, restoring the parts to their original position and condition. The air pressure may be thereafter restored to the desired normal pressure.

It will thus appear that the greater part 35 of the air displaced in the pipe system is quickly removed therefrom through the exhaust valve 20, which should be at a point remote from the sprinkler heads 12, so that no injurious effects will be caused thereby. 40 My improved construction is remarkable for its extreme simplicity, the number of moving parts being reduced to a minimum. It will also be noticed that no resetting of the apparatus is necessary, other than the opening 45 of the valves 14 and 28 to drain the water out of the system.

Having thus described my invention it will be evident that changes and modifications can be made therein by those skilled 50 in the art within the spirit and scope of my invention as set forth in the claims, and I do not wish to be otherwise limited to the details herein disclosed, but what I claim is:—

55 1. An air exhauster for dry pipe systems comprising an air exhaust chamber, an inlet connection to said chamber from said pipe system, said chamber having also an exhaust opening, a valve for closing said exhaust opening, an air storage chamber, and means to open and close said valve, said valve being opened by excess air pressure in said storage chamber and being closed upon the occurrence of excess air pressure in said 60 exhaust chamber.

2. An air exhauster for dry pipe systems comprising an air exhaust chamber, an inlet connection to said chamber from said pipe system, said chamber having also an exhaust opening, a valve for closing said exhaust 70 opening, and air pressure operating means to actuate said valve, said inlet connection affording a free and unobstructed passage at all times between said pipe system and said exhaust chamber.

3. An air exhauster for dry pipe systems comprising an air exhaust chamber, an inlet connection to said chamber from said pipe system, said chamber having also an exhaust opening, a valve to close said exhaust opening, an air storage chamber, a lifter for said valve actuated by a relative difference in pressure between said chambers, said lifter having a bleed opening therethrough connecting said chambers, and means to close 80 said opening when said exhaust valve is opened.

4. An air exhauster for dry pipe systems comprising an air exhaust chamber, an inlet connection to said chamber from said pipe 90 system, said chamber having also an exhaust opening, a valve to close said exhaust opening, an air storage chamber, a diaphragm separating said chambers, and means actuated by said diaphragm and rendered effective by difference in air pressure in said chambers to actuate said valve directly.

5. An air exhauster for dry pipe systems, comprising an air exhaust chamber having inlet and exhaust connections, an exhaust 100 valve in said chamber, an air storage chamber having a bleed opening connected with said exhaust chamber, a diaphragm separating said chambers, and a valve lifter on said diaphragm effective to open said exhaust 105 valve upon relative decrease of pressure in said exhaust chamber.

6. An air exhauster for dry pipe systems, comprising an air exhaust chamber, inlet and exhaust passages for said chamber, a 110 valve for said exhaust passage, a frame for said valve movably mounted in said chamber, pressure-controlled means to move said frame and valve, and a contact member adjustably secured to said frame for engagement by said moving means.

7. An air exhauster for dry pipe systems comprising an air exhaust chamber, an inlet connection to said chamber from said pipe system, said chamber having also an exhaust 120 opening, a valve to close said exhaust opening, and means to open and close said valve, said valve being positioned so as to be normally covered with water in said exhaust chamber.

8. An air exhauster for dry pipe systems comprising an air exhaust chamber, an inlet connection to said chamber from said pipe system, said chamber having also an exhaust opening, a valve to close said exhaust open- 130

ing, and means to open and close said valve, said inlet connection being higher than said valve whereby the portion of said exhaust chamber below said inlet connection normally will be filled with water.

9. An air exhauster for dry pipe systems comprising an air exhaust chamber, an inlet connection to said chamber from said pipe system, said chamber having also an exhaust

opening, a valve to close said exhaust opening, and means to actuate said valve, said inlet connections being higher than said valve and means being provided to drain said chamber above said inlet connections.

In testimony whereof I have hereunto affixed my signature.

HJALMAR G. CARLSON.
